UNITED STATES PATENT OFFICE.

ERASTUS E. WINKLEY, OF LYNN, MASSACHUSETTS, ASSIGNOR TO UNITED SHOE MACHINERY COMPANY, OF PATERSON, NEW JERSEY, A CORPORATION OF NEW JERSEY.

SOLE-LEVELING MACHINE.

1,110,663.

Specification of Letters Patent. Patented Sept. 15, 1914.

Application filed January 6, 1913. Serial No. 740,501.

To all whom it may concern:

Be it known that I, ERASTUS E. WINKLEY, a citizen of the United States, residing at Lynn, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The present invention relates to machines for leveling the soles of boots and shoes, and more particularly to machines of this type which comprise a leveling device and a co-operating shoe supporting jack relatively movable to cause a progressive transfer of the pressure over a shoe sole.

Owing to the varying curvature of different portions of a last bottom some portions of the shoe sole require a more extended leveling action than others if the entire sole is to be shaped into conformity with the curvature of the last.

The object of the present invention is to provide a machine for leveling the soles of boots and shoes which operates efficiently to cause all portions of the sole to conform to the curvature of the last without exerting an excessive pressure upon any portion of the last during the leveling operation.

With this object in view, one feature of the invention contemplates the provision in a machine of the class described having a leveling device and a co-operating shoe supporting jack, of mechanism for automatically varying the duration of the leveling pressure exerted upon different portions of the shoe sole.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention: Figure 1 represents a side elevation of a leveling machine embodying the several features of the invention in their preferred form; Fig. 2 is a detail illustrating a side elevation of the mechanism for automatically stopping the oscillation of the jack at predetermined intervals; Fig. 3 is a cross sec-

tion taken upon the line 3—3 of Fig. 2 and showing the mechanism for starting the jack after a predetermined time has elapsed; Fig. 4 is a detail showing a plan view partly in section of the mechanism illustrated in Fig. 2; and Fig. 5 is a detail showing upon an enlarged scale the cam for controlling the starting mechanism.

The illustrated embodiment of the invention is shown in connection with a machine of the type disclosed in the patent to Winkley, 555,548, patented March 3, 1896. This machine is provided with the usual shoe supporting jack 1 pivoted at 2 in the machine frame 3 and oscillated through suitable connections by a cam secured to the cam shaft 5. The leveling device consists of a freely rotatable roll 10 journaled in the outer end of a roll supporting arm 11 and connected to an eccentric 12 which imparts a rapid vibratory movement to the roll as the jack is moved thereunder. The arm 11 is pivotally supported at 13 and a cam 14 is connected to the roll through mechanism fully shown and described in the patent above referred to for tipping the roll to change the relative lateral inclination of the roll and jack as the latter is moved beneath the roll. The cam shaft 5 has a worm wheel 15 secured thereto which is engaged by a driving worm 16 mounted upon the counter shaft 17. The shaft 17 is operated from a drive shaft 18 through a pair of intermeshing spiral gears 19 and 20 secured to the shaft 18 and loosely journaled upon the shaft 17 respectively. The shaft 17 is clutched to the gear 20 through a clutch collar 22 splined to the shaft 17 and arranged to engage with a co-operating clutch member 23 secured to the gear 20. The clutch collar 22 is actuated by a sliding clutch rod 24 connected with a treadle 25 at one end and with the clutch 22 at its opposite end so that upon a depression of the treadle 25 the clutch collar is disengaged from the member 23, stopping the rotation of the shaft 17. The rod 24 is normally moved to maintain the clutch collar 22 engaged by a compression spring 27 interposed between the frame of the machine and a collar 28 secured to the rod 24.

In the majority of shoes the transverse curvature of the last bottom varies considerably at different points lengthwise of the shoe and in order to cause all portions of

the sole to conform substantially to the shape of the last without exerting an excessive pressure, it is desirable to vary the extent of the leveling action upon different portions of the sole. In the simplest and most efficient form of the invention which has yet been devised, this is accomplished by automatically stopping the relative longitudinal movement of the leveling roll and jack at predetermined intervals to cause the leveling roll to operate for an increased length of time upon certain portions of the sole. The length of time during which the relative longitudinal movement of the roll and jack is stopped may be varied as desired, and at the completion of this interval of time, the relative movement of the roll and jack is again resumed.

In the embodiment of the invention shown in the drawings, the oscillation of the jack beneath the roll is stopped at predetermined intervals by a plurality of fingers 30 projecting radially from the worm wheel 15 and arranged to engage successively with a dog 31 secured to the slide rod 24. As the worm wheel is rotated, one of the fingers 30 moves into engagement with the dog 31 to disengage the clutch members 22 and 23, thus stopping the rotation of the shaft 17 and the oscillation of the jack. In the specific embodiment of the invention shown, the fingers are arranged to stop the jack when the roll is positioned above the toe and opposite sides of the shank of the shoe, but it will be obvious to those skilled in the art that the position and number of these fingers may be varied to stop the oscillation of the jack when the roll is positioned above any desired position of the shoe sole. With this construction the rotation of the cam shaft 5 is stopped when the jack is at rest, and the cam 14 does not operate to change the relative lateral inclination of the roll or jack, the angular position of the roll being maintained constant during the time that the jack is stationary.

It is further desirable to provide mechanism for automatically setting the jack oscillating mechanism into operation after a predetermined time has elapsed. To this end the collar 28 carries a vertical cam finger 35 provided with an inclined upper surface arranged to engage with the free end of an arm 36 which is yieldingly connected to a rock shaft 37 journaled in the machine frame. The rock shaft 37 has a collar, 32 secured thereto which is provided with oppositely extending lateral shoulders 26 and 29, as shown clearly in Fig. 2. The arm 36 is provided with a lug 33, and a spring 34 interposed between the shoulder 29 and the lug 33 serves to yieldingly connect the arm 36 and rock shaft 37. The opposite end of the rock shaft 37 is provided with a traveler arm 38 splined thereto, the free end of which

is arranged to engage with the threads of a lead screw 39 secured to the drive shaft 18. In order to normally retain the traveler member disengaged from the lead screw 39, a spring 40 is interposed between the frame 70 of the machine and the shoulder 26 formed upon the collar 32. The traveler member is normally retained in the longitudinal position shown in Fig. 3 by a coiled spring 41 surrounding the shaft 37 and having its opposite ends connected respectively to the frame of the machine and the traveler 38. With this construction, when the inclined face of the finger 35 engages the arm 36, the rock shaft 37 is actuated to move the free end of the traveler member 38 into engagement with the threads of the continuously rotating lead screw 39. When this occurs, the traveler member 38 is traversed longitudinally of the shaft by the lead screw 39, and during this longitudinal traverse, the member is retained in engagement with the lead screw by the member 35 which is held in position beneath the arm 36. It is desired that at the completion of a predetermined length of time, or when the traveler member 38 has completed its traverse of the lead screw 39, the jack 17 shall be reconnected to the drive shaft 18. To this end a trip rod 42 is slidably mounted in bearings 43 formed in the machine frame and is positioned with one end in close proximity to the side face of the member 35. The trip rod is normally retained in the position shown in Fig. 3 by a pin 45 engaging with one of the bearing members 43, and a compression spring 46 interposed between the second bearing 43 and a collar 47 secured to the rod. The traveler member 38 is provided with a depending lower end 50 which is aligned with the end of the rod in order to cause the trip rod to be engaged by the traveler just prior to the completion of its traverse. When this engagement takes place, the trip rod is moved against the finger 35, rocking the finger and the dog 31 out of engagement with the arm 36 and the finger 30 respectively. The rod 42 is then allowed to move longitudinally to engage the clutch, and the shaft 37 is oscillated by the spring 40 to move the traveler member out of engagement with the lead screw 39, after which the traveler is returned to its initial position by the spring 41.

In order to vary the time intervals during which the jack is stopped and the roll vibrates over a single portion of the shoe sole, mechanism is provided for varying the length of the traverse of the member 38. As the oscillation of the jack is conveniently started in every case when the traveler member reaches the same point upon the lead screw, the variation of the time of stopping is accomplished by varying the point at which the traveler member engages with the

lead screw. A cam 55 secured in any desired manner to the cam shaft is provided with a series of lateral projecting cam ribs 56 secured to the cam by bolt and slot connections indicated at 62. The cam 55 is engaged by the free end of a lever 57 fulcrumed at 58 and having its opposite end connected to a slide 59 through a link 60. The slide 59 is loosely mounted upon the rock shaft 37 and a spring 61 normally retains the slide in a retracted position, as shown in Fig. 3. With this construction, when the end of the lever 57 engages with one of the cam ribs 56, it is oscillated to move the slide 59 in a longitudinal direction. This movement of the slide positions the traveler member opposite different portions of the lead screw 39, consequently varying the length of traverse of the member. Each of the cams 56 is located in advance of its corresponding finger 30 in order to position the traveler member properly with relation to the lead screw 39 before the member is moved into engagement therewith. It will be noted that the normal position of the traveler member 38, which is determined by the engagement of the lever 57 with the face of the cam 55, is beyond the commencement of the lead screw thread. The purpose of this arrangement is to enable the machine to be automatically stopped at the completion of the cycle of operations without setting into operation the mechanism for restarting the jack. To this end in the illustrated embodiment of the invention, one of the fingers 30 is not provided with a corresponding cam rib 56 and when this finger moves into engagement with the dog 31 to operate the train of mechanism for stopping the machine, the free end of the lever 57 is positioned as shown in Fig. 4, causing the traveler member 38 to move into engagement with the cylindrical end of the lead screw 39, stopping the machine for an indefinite length of time until restarted by the operator.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A sole leveling machine having, in combination, a leveling device, a shoe supporting jack, mechanism for changing the relative longitudinal position of the leveling device and jack, and additional mechanism for automatically varying the duration of the leveling action upon different portions of the shoe sole.

2. A sole leveling machine having, in com-

bination, a leveling device, a jack, mechanism for changing the relative longitudinal position and lateral inclination of the leveling device and jack, and additional mechanism for automatically varying the duration of the leveling action upon different portions of a shoe sole.

3. A sole leveling machine having, in combination, a leveling device, a shoe supporting jack, mechanism for securing a relative longitudinal movement of the leveling device and jack, and means for automatically stopping said mechanism for predetermined intervals to cause the leveling device to operate for an increased length of time upon certain portions of the sole.

4. A sole leveling machine having, in combination, a leveling device, a jack, mechanism for changing the relative longitudinal position and lateral inclination of the leveling device and jack, and additional mechanism for automatically stopping the relative longitudinal movement during the continuous operation of the machine and for maintaining the relative lateral inclination of the roll and jack constant while the jack is stationary.

5. A sole leveling machine having, in combination, a leveling device, a shoe supporting jack, mechanism for moving the jack longitudinally beneath the leveling device, and means for automatically stopping said mechanism for a predetermined length of time during the leveling operation to vary the extent of the leveling action upon different portions of the sole.

6. A sole leveling machine having, in combination, a leveling roll, means for vibrating the roll, a shoe supporting jack, mechanism for oscillating the jack beneath the roll, and means for automatically stopping said mechanism at predetermined intervals during the continuous operation of the machine to cause the roll to vibrate for an increased length of time over certain portions of the shoe sole.

7. A sole leveling machine having, in combination, a leveling roll, a shoe supporting jack, mechanism for oscillating the jack beneath the roll, means for stopping said mechanism, and means for automatically setting said mechanism into operation at the completion of a predetermined length of time.

8. A sole leveling machine having, in combination, a leveling device, a shoe supporting jack, mechanism for imparting a relative longitudinal movement to the leveling device and jack, and means for stopping the relative longitudinal movement for a predetermined length of time, having provision for adjustment to vary the portion of the sole upon which the extended leveling pressure is exerted.

9. A sole leveling machine having, in com-

bination, a leveling device, a shoe supporting jack, means for moving the jack beneath the leveling device, means for stopping the movement of the jack for a predetermined length of time, and mechanism for varying the length of time during which the jack is stopped.

10. A sole leveling machine having, in combination, a leveling device, a shoe supporting jack, a continuously rotated drive shaft, connections between the drive shaft and jack, mechanism for automatically disconnecting the jack from the drive shaft, and means controlled by the continuously rotated drive shaft for reconnecting the jack to the drive.

11. A sole leveling machine having, in combination, a leveling roll, a shoe supporting jack, a drive shaft, a lead screw mounted upon the drive shaft, connections between the drive shaft and jack, a traveler arranged to engage with the lead screw and be moved thereby; and a trip member contacting with the traveler at the completion of its traverse to establish an operative connection between the drive shaft and jack.

12. A sole leveling machine having, in

combination, a leveling roll, a jack, a continuously operated drive shaft, operative connections between the drive shaft and jack, mechanism for disconnecting the jack from the drive shaft, a lead screw mounted upon the drive shaft, a traveler member, and mechanism for automatically connecting the traveler member with the lead screw to reestablish the operative connection between the drive shaft and jack at the completion of a predetermined length of time.

13. A sole leveling machine having, in combination, a leveling device, a shoe supporting jack, means for securing a relative longitudinal movement of the leveling device and jack, a continuously rotated drive shaft, an intermittently operated cam shaft connected to the jack, connections between the two shafts, means operated by the cam shaft for disconnecting the two shafts, and mechanism operated by the drive shaft for reconnecting the two shafts at the completion of a predetermined length of time.
